UNITED STATES PATENT OFFICE.

CHARLES F. PYM, OF LYNN, MASSACHUSETTS, ASSIGNOR TO UNITED SHOE MACHINERY CORPORATION, OF PATERSON, NEW JERSEY, A CORPORATION OF NEW JERSEY.

LASTING MECHANISM.

1,413,614.

Specification of Letters Patent. Patented Apr. 25, 1922.

Original application filed December 11, 1913, Serial No. 806,126. Divided and this application filed May 21, 1918. Serial No. 235,820.

To all whom it may concern:

Be it known that I, CHARLES F. PYM, a subject of the King of Great Britain, residing at Lynn, in the county of Essex and State of Massachusetts, have invented certain Improvements in Lasting Mechanisms, of which the following description, in connection with the accompanying drawings, is a specification, like reference characters on 10 the drawings indicating like parts in the several figures.

This invention relates to lasting mechanism,—in particular, to gripper mechanism for pulling shoe materials over lasts or 15 other forms in the making of shoes,—, and is a division of the subject-matter of my co-pending application for Letters Patent for improvements in lasting machines, Serial No. 806,126, filed Dec. 11, 1913, upon which 20 Patent No. 1,274,590 was granted on August 6, 1918.

In the use of gripper mechanisms, or, as they are alternatively termed, pincer mechanisms, for pulling the upper over the last 25 and particularly in connection with power operated lasting machinery, trouble is frequently experienced through the failure of the gripper jaws properly to grip the shoe stock between them. This defect, in many 30 cases, is due to the relatively close relation of the open jaws and the consequent small stock-receiving opening and also to the action of the movable jaw in closing. In automatic machines, particularly, a quick 35 opening and closing movement with provision for wide stock-receiving spacing is desirable and this can most efficiently be secured by a construction requiring comparatively slight movement of the jaw actuating means.

This invention provides a novel construction and arrangement of gripper mechanism designed to accelerate relative closing and opening movements of the gripper jaws in 45 order to permit the jaws to present a wide stock receiving opening without the necessity for an undesirable extent of movement of the operating means in opening the jaws or in closing them on the work. In the construction shown this object is attained by 50 the use of connecting links extending across from one jaw to the other and arranged in non-parallel relation to produce an angular divergence between the jaws in opening. In

the illustrative construction of the jaws, the 55 relative closing and opening movements, under the control of the links, are effected by operating means which moves in a direction substantially parallel to the direction of pull of the gripper and imparts to one of the 60 jaws a longitudinal movement relatively to the other. Still further to accelerate the relative closing and opening movements of the jaws, the controlling links provided in the construction shown are of different 65 lengths.

A further feature of the invention consists in a novel construction of gripper mechanism in which the gripper jaws are closed yieldingly on the upper and the gripper is operated positively to pull the upper. 70 In the construction shown the pulling movement of the gripper is effected by means which operates independently of the means whereby the jaws are closed, the latter 75 means maintaining the jaws yieldingly in closed position during the pull.

These and other features and advantages will be more fully apparent by reference to the following detailed specification and to 80 the accompanying drawing, illustrating one embodiment of the invention.

In this drawing,

Fig. 1 is a view of the gripper mechanism in open position with the margin of the upper stock of a supported shoe inserted within the gripper jaws, and

Fig. 2 is a view with the jaws closed and pulling the stock over the end of the last.

The relatively stationary or fixed jaw of 90 the gripping mechanism is in the form of a downwardly and forwardly curving lip 149 formed at the lower end of a head 148 hollowed or recessed above said lip to form a housing to receive the shank portion of 95 the movable jaw and the operating mechanism and having its upper end provided with a cylindrical shank 150 extending through and slidably in a bore formed in the end of a supporting frame or carrier 156. 100 A collar 157 adjustably fixed by a set screw to the upper end of the stem 150 retains said stem on the frame 156.

The movable jaw 151 is mounted in the recessed portion of the head 148 by means 105 of a short link 152 pivotally connecting the upper end of the jaw shank to the walls of the head and by a lever pivoted between its

ends within the recessed portion of the head and having its outer arm 153 pivotally connected to the movable jaw at a point intermediate of its ends and nearer the extremity 5 of said jaw than the pivot point of the lever is to the extremity of the fixed jaw, this arm 153 and link 152 being arranged in divergent or non-parallel relation and constituting non-parallel links of unequal lengths connecting the movable jaw and the stationary 10 jaw and diverging substantially in the direction in which the jaws point, both the non-parallel arrangement and the inequality of length of the links serving to increase the 15 reaching out action or the angular divergence of the movable jaw from the other jaw in opening as well as to accelerate the opening and closing movements. The relative arrangement of these links 152, 153 is 20 such that the movable jaw 151 is guided for a longitudinal movement relatively to the stationary jaw 149 characterized by coincident swinging of the movable jaw toward and from the stationary jaw in a path 25 which is approximately at right angles to the plane of the co-operating gripping face of the stationary jaw, the gripping face of the movable jaw in the last stages of its closing movement assuming a substantially 30 parallel relation to the gripping face of the stationary jaw. In open position the jaws present an upper receiving opening of relatively large area which converges inwardly of the jaws. The lever which is 35 pivotally mounted within the recessed portion of the head 148 with its forward end 153 connected to the movable jaw 151 extends rearwardly therefrom and is formed with an enlarged rear end having an elongated 40 opening therein receiving a roller 154 carried by and offset from the lower end of an operating rod or slide 155 which is guided within the head 148 and freely movable through a bore in the supporting frame 45 156. This rod extends to a point above the frame 156 and has its upper end threaded to receive a flanged threaded sleeve 170 which is encircled by a coiled spring 168. The upper end of the spring abuts against 50 the flanged end of the sleeve 170 and its lower end abuts against a washer 169 seated over an opening in the forward end of an operating arm 158 which, together with the frame 156, is journaled at 159 on a suitably 55 supported spindle and is operated by suitable means such as a cam 166 acting against a roll on the extended end of the arm to pull the closing rod 155 and impart movement to the jaw 151 to clamp the upper materials 60 between it and the relatively stationary jaw 149, and then by further movement to increase the closing pressure of the jaws on the upper. This arrangement permits a relatively strong gripping force to be transmitted to the movable jaw, the spring 168

preventing excessive closing pressure from being transmitted from the arm 158.

After the jaws have been closed on the upper as above described, the frame 156 is swung upwardly about its pivot 159 by the 70 action of a cam 162 similar to the cam 166, and by engagement with the collar 157 lifts the gripper jaws bodily and unyieldingly to pull the upper while the jaws are held yieldingly closed by the action of the spring 168. 75 During this upper pulling movement of the gripper the last is held against movement in the direction of the pull by means of a shoe rest 124. As the upward movement of the gripper continues, further operative 80 movement may be imparted to the arm 158 in order to insure that the tension of the spring 168 shall remain effective to hold the jaws in secure gripping engagement with the stock. 85

Having described my invention, what I claim as new and desire to secure by Letters Patent of the United States is:—

1. In mechanism of the class described, relatively movable gripper jaws, and a pair 90 of divergent link members connecting said jaws for relative closing and opening movements in approximately straight line paths which are in approximately right angular relation to the planes of the co-operating 95 gripping faces of said jaws.

2. In mechanism of the class described, relatively movable gripper jaws, and a pair 100 of link members arranged in divergent relation and connecting said jaws for relative closing and opening movements, one link member being connected to said jaws at points nearer their gripping extremities than the other members and at different distances from said extremities. 105

3. In mechanism of the class described, relatively movable gripper jaws, and a plurality of links arranged in divergent relation and each pivotally interconnecting said jaws and arranged to position said jaws, in 110 open relation with their co-operating gripping faces presenting an inwardly converging stock receiving opening and relatively to move said jaws for closing in a path approximately in right angular relation to the 115 co-operating gripping faces of said jaws.

4. In mechanism for pulling an upper over its last, a movable gripper jaw, a relatively stationary gripper jaw, divergent link members pivotally connecting said jaws 120 for closing and opening movements of the movable jaw in a path approximately at right angles to the co-operating gripping face of the stationary jaw, and means for first yieldingly closing said jaws and then 125 for bodily retracting them to pull the gripped upper.

5. In mechanism of the class described, a movable gripper jaw, a relatively stationary gripper jaw, divergent link members piv- 130

totally connecting said jaws for closing and opening movements of the movable jaw in a path approximately at right angles to the co-operating gripping face of the stationary 5 jaw, one of said link members being connected to the movable jaw at a point intermediate of its ends and forming one arm of a jaw closing lever, and closing means co-operating with the other arm of said lever 10 to move said jaw toward and from gripping position.

6. In a pulling-over mechanism, shoe holding means, a bodily retractile gripper having opening and closing jaws, and two non- 15 parallel links each extending across from one jaw to the other, whereby relative longitudinal movement of one jaw is accompanied by a swinging apart thereof from the other jaw.

7. In a pulling-over mechanism, shoe holding means, a bodily retractile gripper having opening and closing jaws, non-parallel links connecting said jaws, whereby relative longitudinal movement of the jaws is accompanied by relative swinging movement to close or open the jaws, and means for moving one jaw to close the gripper, said means including a yielding resistance medium arranged to cause the gripper closing operation to be effected yieldingly.

8. In mechanism for pulling an upper over its last, relatively movable gripper jaws connected for opening and closing relative movements, jaw closing means movable 35 to close the gripper yieldingly, and gripper operating means arranged for positive gripper retracting movement.

9. In mechanism for pulling an upper over its last, a stationary gripper jaw, a 40 movable gripper jaw, a pair of non-parallel links connecting said jaws for opening and closing relative movements, an operating member connected to said movable jaw and arranged to close the gripper yieldingly, 45 and a second operating member arranged for positive movement to retract the gripper.

10. In mechanism of the character described, the combination with carrying means for pincers, of pincers comprising a 50 hollow head portion formed with a depending fixed jaw, a movable jaw having a portion extending within the hollowed portion of the head, a pair of nonparallel link members connecting said fixed and movable jaws 55 for opening and closing movements, one of said link members being extended from the fixed jaw and forming a lever, a rod connected to the extended end of the lever and extending upwardly beyond said carrying 60 means, and operating means connected to said rod.

11. In mechanism of the character described, the combination with carrying means for pincers, of pincers comprising a 65 hollow head portion formed with a fixed

jaw, a movable jaw having a portion extending into the hollow head, a link within the hollow head connecting the end of the movable jaw with the walls of said head, a lever pivoted intermediate its ends within 70 the hollow head with one end pivotally attached to the movable jaw, an upwardly extending rod guided within the head and connected at its lower end to the opposite end of said lever, means on the head for attachment to the carrying means, an operating lever having an opening therein through which the rod extends, an adjustable nut on the upper end of the rod, and a spring sleeved on the rod between the nut and the 80 operating lever.

12. In mechanism of the character described, the combination of a head having a recess therein and provided with a lower gripping jaw curved downwardly and forwardly from the lower end thereof, a co-operating jaw, a jaw closing lever fulcrumed on the head within the recess and to the front end of which the last named jaw is pivoted between its ends, an operating slide 90 for the lever, and a jaw motion controlling link pivotally connecting the upper end of said last named jaw to the head.

13. In mechanism for pulling an upper over its last, a gripper comprising a fixed 95 jaw, a movable jaw, links connecting the jaws which are divergent in the direction in which the jaws point to increase the reaching out movement of the movable jaw, and operating means for the movable jaw.

14. In mechanism for pulling an upper over its last, a gripper comprising a fixed jaw, a movable jaw, links of unequal lengths connecting the jaws, the outer link being the shorter to increase the reaching out movement of the movable jaw, and operating 105 means for the jaws.

15. In mechanism of the class described, a pair of gripper jaws, a pair of connecting links extending across from one jaw to the 110 other and arranged in non-parallel relation to cause an angular divergence between the jaws in opening, and means movable in directions substantially parallel to the direction of pull of the gripper to impart relative 115 closing and opening movements to the jaws under the control of said links.

16. In mechanism of the class described, a pair of gripper jaws, a pair of connecting links extending across from one jaw to the 120 other to permit relative movement between the jaws, one of said links being longer than the other to produce an angular divergence between the jaws in opening, and means for effecting relative closing and opening movements of the jaws under the control of said links.

17. In mechanism of the class described, a pair of gripper jaws, a pair of connecting links extending across from one jaw to the 130

other at different respective distances from the gripping faces of the jaws, said links being arranged in non-parallel relation and the link which is the nearer to the gripping faces being longer than the other link, and means for effecting relative closing and opening movements of the jaws under the control of said links.

18. In mechanism of the class described, 10 relatively movable gripper jaws, means movable substantially in the direction of the pull of the gripper for closing said jaws yieldingly on the work, and additional means movable in substantially the same direction for imparting upper pulling movement to said jaws.

19. In mechanism of the class described, 20 relatively movable gripper jaws, means for closing said jaws yieldingly on the work, and means for moving said jaws positively to pull the upper while they are held yieldingly closed by said first-named means.

20. In mechanism of the class described, a gripper comprising a fixed jaw member, a

movable jaw member, a pivotal link connecting the movable member to the fixed member, and a second positive connecting device connecting the jaw members at points other than the points of connection of said link, said other points being separated in the plane of movement of the movable jaw member and at unequal distances from said points of connection of the link.

21. In mechanism of the class described, a gripper comprising a fixed jaw member, 35 a movable jaw member, a pivotal link connecting the movable member to the fixed member, and a second link positively connecting said members and constructed and arranged relatively to said members and the 40 first named link to cause the gripping faces of the jaws to diverge when open and to extend in substantially parallel relation to each other in the last stages of closing movement of the movable jaw member.

In testimony whereof I have signed my name to this specification.

CHARLES F. PYM.
